CLAIM

The ornamental design for a food serving tray, as shown.

DESCRIPTION

FIG. 1 is a top perspective view of a food serving tray showing my new design;
 FIG. 2 is a top plan view thereof;
 FIG. 3 is a bottom plan view thereof;
 FIG. 4 is a front elevational view thereof;
 FIG. 5 is a rear elevational view thereof;
 FIG. 6 is a left side elevational view thereof;
 FIG. 7 is a right side elevational view thereof;

FIG. 8 is a top perspective view of a food serving tray showing a second embodiment of my new design;
FIG. 9 is a top plan view thereof;
FIG. 10 is a bottom plan view thereof;
FIG. 11 is a front elevational view thereof;
FIG. 12 is a rear elevational view thereof;
FIG. 13 is a left side elevational view thereof;
FIG. 14 is a right side elevational view thereof;
FIG. 15 is a top perspective view of a food serving tray showing a third embodiment of my new design;
FIG. 16 is a top plan view thereof;
FIG. 17 is a bottom plan view thereof;

FIG. 18 is a front elevational view thereof;
FIG. 19 is a rear elevational view thereof;
FIG. 20 is a left side elevational view thereof;
FIG. 21 is a right side elevational view thereof;
FIG. 22 is a top perspective view of a food serving tray showing a fourth embodiment of my new design;
FIG. 23 is a top plan view thereof;
FIG. 24 is a bottom plan view thereof;
FIG. 25 is a front elevational view thereof;
FIG. 26 is a rear elevational view thereof;
FIG. 27 is a left side elevational view thereof; and,
FIG. 28 is a right side elevational view thereof.
